FULLING MILL

Robert L. Dawson, Piqua, Ohio, assignor to The
Orr-Felt & Blanket Company, Piqua, Ohio

Application March 25, 1938, Serial No. 198,143

11 Claims. (Cl. 26—21)

The invention relates to fulling mills used in shrinking fabrics and it relates primarily to the so-called crimp boxes of such mills. The material being fulled, after being treated with a soap solution or in any other desired way, is pushed by two suitable rollers through the crimp box, the top of which is held yieldably depressed upon the material by weights and levers or in other appropriate ways, thereby causing the desired crimping of the goods. The effect of the crimp box on the goods is dependent to a large extent on the width of said box, the results being non-uniform and unsatisfactory if the box be either too narrow or too wide. It is one of the objects of my invention to provide a crimp box which may be readily varied in width, and in one embodiment of the invention, one side of the box may be adjusted toward or from the other side while the mill is in operation. The advantages of an adjustable side to vary the width of the box applies particularly to papermakers' felts which are woven in various widths to fit all types of papermaking machines. The advantages also apply to piece-goods where a mill might change its production from light weight 8 oz. broadcloth to heavy weight 30 oz. overcoating. As above indicated, maximum fulling and felting are obtained when the cloth, as it runs through the crimp box, fills the box rather full, and by means of my invention, the operator may quickly and easily vary the width of the box according to the width of the felt or cloth or the volume going through the box, in order to insure the most efficient operation of the mill.

In carrying out the above end, a further aim is to make novel provision whereby the action taking place within the crimp box may be readily observed, permitting adjustment until the best result is obtained.

With the foregoing in view, the invention resides in the novel subject matter hereinafter described and claimed, description being accomplished by reference to the accompanying drawings.

Fig. 1 is a side elevation partly broken away, showing a portion of a fulling mill embodying the present invention.

Fig. 2 is a vertical transverse sectional view on line 2—2 of Fig. 1.

Fig. 3 is a fragmentary view similar to a portion of Fig. 2 but showing the crimp box adjusted to a narrower width and provided with a narrower top.

Fig. 4 is a detail horizontal sectional view on line 4—4 of Fig. 2.

In the drawings above briefly described, a preferred construction has been illustrated, and while this construction will be rather specifically described, it is to be understood that variations may be made within the scope of the invention as claimed.

The fulling mill casing 5 and its frame-work 6 may be of conventional construction, one side of said casing being provided with the usual loading doors 7 and 8, the latter of which gives access to the crimp box 9 when opened. At the front end of this crimp box, the usual upper and lower rollers 10 and 11 are shown for pushing the material through the box, the upper roller being held yieldably toward the lower roller, for example, by mounting it upon bell cranks such as 12 and connecting hydraulic or other suitable means 13 with said bell cranks. Conventional material-guiding means are indicated at 14 and 15 in front of the rollers 10 and 11. The numbers 17, 18, 19, 20, 21 and 22 denote conventional means for depressing the top 23 of the fulling box 9 to exert desired pressure upon the material being fulled.

The bottom 25 of the fulling or crimp box 9 is rigidly secured to brackets 26 fastened to one of the side walls 27 of the casing 5. The two vertical side walls of the box are denoted at 28 and 29 respectively. The wall 29 is hingedly supported at 30 in a conventional way to allow outward swinging of said wall when the door 8 is opened, permitting easy threading of the material through the box. In the present showing, the hinges 30 connect the wall 29 with two brackets 31 secured to suitable portions of the frame 6. Brace arms 32 are shown secured to the wall 29 at one end, and at their other ends cooperable with suitable latches 33 carried by the brackets 31 for normally holding said wall 29 in operative position, release of said latches, however, allowing outward swinging of said wall when required. Any suitable means is provided for holding the lower edge of the wall 29 and the bottom 25 in tight engagement with each other, cam levers 34 being shown for this purpose.

The edges of the side wall 28 are preferably flanged as shown at 35, and the lowermost of these flanges rests slidably upon the box bottom 25 to allow adjustment of said wall 28 toward and from the wall 29. In the present disclosure, a horizontal screw 36 is connected with and projects laterally outward from the wall 28, said screw being guided by a fixed bracket 37 secured to the frame 6 at the outer side of the wall 27. The bracket 37 also serves to rotatably and stationarily mount a hand wheel 38, the hub 39 of which is 55

threaded on the screw 36. Rotation of the hand wheel 38 upon the screw 36 will therefore effect inward or outward adjustment of the wall 28, as may be desired. A suitable locking wheel 40 may be threaded on the screw to lock said screw and the wheel 38 against relative rotation after the desired adjustment has been obtained.

The screw 36 may be connected in any preferred manner with the wall 28. For illustrative purposes, a channel bar 41 is shown extending vertically between the flanges 35 and secured to the wall, said channel bar having an opening 42 through which the inner end of the screw 36 passes, collars 44 being secured on said screw at the inner and outer sides of said channel bar. The screw may either be held against rotation or may be permitted to rotate by the connecting means between said screw and the wall 28, but if said screw be permitted to rotate by this connection, it will be necessary to provide the outer end of said screw with a knob or wheel 45 to be held in one hand while loosening the locking wheel 40 or rotating the hand wheel 38 with the other hand.

25 The box top 23 is pivotally and detachably mounted on a bolt 46 by means of which it is connected with a bracket 47, said bracket being secured to the side 27 of the casing 5. A number of tops will be furnished of different widths, and after adjusting the side wall 28 into the desired spaced relation with the side wall 29, a top of proper width will be mounted on the bolt 46.

I contemplate the use of some appropriate transparent material such as plastacel, Celluloid or shatter-proof glass, in such manner as to permit viewing of the actual conditions within the crimp box 24. For illustrative purposes, I have shown a transparent panel 48 in the side wall 29, but that entire wall or the entire box may 40 be made of such transparent material. By looking through this panel with the door 8 open, the effect of the crimping box upon the material may be readily observed, and the box may be adjusted until the best results are obtained.

45 From the foregoing, taken in connection with the accompanying drawings, it will be seen that novel and advantageous provision has been made for carrying out the objects of the invention, and while preferred features have been disclosed, 50 attention is again invited to the possibility of making variations within the scope of the invention as claimed, the present disclosure being illustrative rather than limiting.

I claim:

55 1. In a fulling machine having a casing and material pushing means therein; a crimp box in said casing through which the material is pushed by said pushing means, said crimp box having vertical side walls mounted for relative adjustment toward and from each other, and means extending from said crimp box to the exterior of said casing for relatively adjusting said side walls according to the width of the material to be fulled and for holding said walls in fixed relation after adjustment.

2. In a fulling machine having a casing, and material pushing means therein; a crimp box in said casing through which the material is pushed by said pushing means, said crimp box having two vertical side walls one of which is capable of adjustment toward and from the other, and means connected with said one side wall and extending to the exterior of the casing for adjusting said one side wall inwardly or outwardly

according to the width of the material to be fulled and for holding said one side wall in fixed relation with said other side wall after adjustment.

3. In a fulling machine having a casing and material pushing means therein; a crimp box in said casing through which the material is pushed by said pushing means, said crimp box having two vertical side walls one of which is capable of adjustment toward and from the other, a bracket secured to the exterior of the casing at the side 10 thereof adjacent said adjustable side wall, a hand wheel rotatably mounted on said bracket, and a screw operatively engaged with said hand wheel and said adjustable side wall to adjust the latter inwardly or outwardly and to hold it in fixed 15 position after adjustment.

4. In a fulling machine having a casing and material pushing means therein; a crimp box in said casing through which the material is pushed by said pushing means, said crimp box comprising a bottom fixedly mounted in said casing, two vertical crimp box side walls in cooperative relation with said bottom, one of said side walls resting slidably on said bottom for adjustment toward and from the other of said side walls, the latter 25 being hingedly mounted for outward swinging to facilitate threading of the material through the machine, and a depressible crimp box top between said side walls; and means extending from said one side wall to the exterior of the casing for adjusting said one side wall toward and from the hinged side wall according to the width of the material to be fulled, and for fixedly holding said one side wall after adjustment.

30 5. A structure as specified in claim 4; together with means detachably mounting said top, allowing a top of proper width to be substituted according to the spacing into which said side walls may be relatively adjusted.

35 6. In a fulling mill, a casing having spaced vertical side walls and a loading door in one thereof, brackets secured to the other of said walls and projecting inwardly therefrom opposite said loading door, a crimp box bottom secured upon said brackets, additional brackets secured to said one wall and projecting inwardly therefrom at the upper end of said loading door, a vertical crimp box side wall hinged to the latter brackets to swing outwardly when said loading door is opened, releasable means for normally holding said crimp box side wall in fixed relation with said bottom, another vertical crimp box side wall resting slidably upon said bottom, means connected with this crimp box side wall and extending to the exterior of said casing for adjusting this side wall toward and from the hinged side wall according to the width of the material to be pushed through the crimp box, said means being also operative to hold said other crimp box wall in fixed position after adjustment, another 40 bracket secured to said other casing wall above said side walls, and a depressible crimp box top pivoted to this bracket and extending between said side walls, said crimp box top being detachably mounted, permitting a top of another width 45 to be substituted when the relative adjustment of the crimp box side walls is such as to necessitate such substitution.

7. In a fulling machine having material pushing means; a crimp box through which the material is pushed by said pushing means, said crimp box having a bottom, and two vertical side walls mounted for relative adjustment toward and from each other according to the material to be fulled, at least one of said side walls resting slid- 50

ably upon said bottom for adjustment transversely thereof, means whereby said side walls may be secured in fixed relation after relative adjustment, and means whereby a top suitable to the relative spacing of said side walls may be mounted for vertical movement between said side walls.

8. In a fulling machine having material pushing means; a crimp box through which the material is pushed by said pushing means, said crimp box having a bottom, a fixed vertical side wall, and a shiftable vertical side wall resting slidably upon said bottom for adjustment toward and from said fixed side wall according to the material to be fulled; means whereby said shiftable side wall may be secured after adjustment, and means whereby a top suitable to the relative spacing of said side walls may be mounted for vertical movement between said side walls.

9. In a fulling machine having a casing and material pushing means therein; a crimp box in said casing through which the material is pushed by said pushing means, said crimp box having vertical side walls mounted for relative adjustment toward and from each other, and means extending from said crimp box to the exterior of said casing for relatively adjusting the side walls according to the width of the material to be fulled.

10. In a fulling machine having a casing and material pushing means therein; a crimp box in said casing through which the material is

pushed by said pushing means, said crimp box comprising a bottom fixedly mounted in said casing, two vertical crimp box side walls in cooperative relation with said bottom, one of said side walls resting slidably on said bottom for adjustment toward and from the other of said side walls, the latter being hingedly mounted for outward swinging to facilitate threading of the material through the machine, and a depressible crimp box top between said side walls; and means for securing said one side wall in fixed relation with said hinged side wall after adjustment.

11. In a fulling machine having a casing and material pushing means therein; a crimp box in said casing through which the material is pushed by said pushing means, said crimp box comprising a bottom fixedly mounted in said casing, two vertical crimp box side walls in cooperative relation with said bottom, one of said side walls resting slidably on said bottom for adjustment toward and from the other of said side walls, the latter being hingedly mounted for outward swinging to facilitate threading of the material through the machine, and a depressible crimp box top between said side walls; and means extending from said one side wall to the exterior of the casing for adjusting said one side wall toward and from the hinged side wall according to the width of the material being fulled.
